UNITED STATES PATENT OFFICE.

MARK L. HARNED, OF WASHINGTON, DISTRICT OF COLUMBIA.

FLUID-PRESSURE-ACTUATED VALVE.

1,291,862.

Specification of Letters Patent. Patented Jan. 21, 1919.

Application filed March 12, 1918. Serial No. 221,990.

To all whom it may concern:

Be it known that I, MARK L. HARNED, a citizen of the United States, residing at Washington, District of Columbia, have invented certain new and useful Improvements in Fluid-Pressure-Actuated Valves; and I do hereby declare the following to be a full, clear, and exact description of the invention, such as will enable others skilled 10 in the art to which it appertains to make and use the same.

My invention relates to fluid pressure actuated valves and particularly to that type wherein the supply and exhaust of fluid pressure to the main cylinder is controlled by a fluid pressure operated main valve and the actuation of the latter in turn controlled by a fluid pressure operated auxiliary valve.

It is my purpose to provide a valve mechanism of the type named wherein the possibility of premature operation of the auxiliary valve is obviated and resulting short stroke of the engine piston prevented; such short stroke of the engine piston now frequently occurring as the result of the accumulation of fluid pressure between the packing rings thereof and its premature delivery to the actuating piston of the auxiliary valve.

Furthermore, it is my purpose to provide a two head piston for actuating the main valve, the heads of said piston having different diameters, with the one of smaller diameter constantly connected to the exhaust and thereby necessitating the control of fewer passages by the auxiliary valve to effect the correct actuation of the main valve.

I will describe my invention as applied to 40 a steam engine although it will be apparent that it is readily adapted for use in connection with any fluid pressure operated engine and that it is susceptible to changes in forms and proportions without departing 45 from the scope of the invention as set forth in the appended claims.

In describing my invention reference will be had to the accompanying drawings wherein like characters of reference denote 50 corresponding parts in the several views and in which—

Figure 1 is a diagrammatic view showing my invention applied to a vertical direct acting engine;

Fig. 2, a section on the line 2--2 of Fig. 1;

Fig. 3, a plan view of the seat upon which the main valve slides; and

Fig. 4, a detail section illustrating the structure for, obviating the possibility of short stroke of the engine piston. 60

It will be understood that the diagrammatic view shown in Fig. 1 is of the developed type with respect to the steam chest of the engine so as to bring both the main and auxiliary valves into view with the latter above the former. The actual arrangement of the main and auxiliary valves in respect to the engine piston and cylinder would depend upon the use of and conditions surrounding the complete engine in 70 actual operation.

Referring now to the drawings the engine cylinder is indicated at A, the steam chest at B and the engine piston at C. This piston C is provided with the 75 usual packing rings 8 and 9. The exhaust passage or port of the cylinder A is shown at t, while the steam inlet for the steam chest is shown at a. The exhaust passage t is connected to the interior of the 80 steam chest B by a passage e, while opposite ends of the cylinder A are connected respectively with the interior of the steam chest by passages c and d. The ends of the passages c, d and e which open into the steam chest 85 are controlled by a main valve 6 provided with a cavity m adapted to connect the passage e with either the passage c or d according to the position of the valve. This valve 6 is operated by a piston formed of 90 mutually connected heads 2 and 3, the former having a greater diameter than the latter. The space between the heads 2 and 3 is constantly in communication with the steam inlet a, while the outer end of the 95 head 3 is constantly in communication with the exhaust passage t.

To control the movements of the main valve 6 I employ an auxiliary valve 7 mounted in the steam chest B and actuated by a piston having mutually connected heads 4 and 5. The space between the pistons 4 and 5 is maintained constantly in communication with the steam inlet a by a passage b. Steam is supplied to and exhausted from the outer end of the head 2 through a passage f, which, during the exhaust of steam from the outer end of the head 2, is placed in communication with the passage g through a cavity q in the valve 7, said passage g 100 105 110 115 120

merging at one end into the exhaust passage *t*. The supply and exhaust of steam to and from the outer ends of the heads 4 and 5 is effected through passages *l* and *k* respectively, which passages open through the seat of the valve 6, as shown in Fig. 3, and are controlled by said valve. Live steam for effecting the actuation of the valve 7 is obtained from the cylinder A through 10 tripping ports *i* and *j* which open respectively into the cylinder at points adjacent the lower and upper ends thereof, said ports being so located as to be in communication with the live steam end of the cylinder at 15 the termination of each stroke of the piston C. These ports *i* and *j* also open through the seat of the valve 6 and are controlled by the latter. The valve 6 is further provided with a cavity *n* and passages *o* and *p*, 20 said passages opening at one end into the cavity *m*. This cavity *n* and the passages *o* and *p* control the passages *l* and *k* and also the tripping ports *i* and *j* as will hereinafter appear. 25 In operation live steam enters at *a*, passes into the space between the heads 2 and 3 and thence through the passage *c* into the cylinder A, forcing the piston C downward. The steam below the piston C exhausts 30 through the passage *d*, cavity *m*, passage *e* and passage *t*. As the piston C reaches the end of its downward stroke tripping port *i* is uncovered, admitting pressure steam which passes through said port, cavity *n*, 35 passage *k*, and enters behind piston head 5 forcing said piston head, valve 7, and piston head 4 to the right; the outer end of the piston head 4 being open to exhaust through the passage *l*, passage *o*, cavity *m*, passage *e*, 40 and passage *t*. When the auxiliary valve 7 moves to the right the live steam operating against the outer end of the piston head 2 exhausts through the passage *f*, cavity *g*, passage *g*, 45 and exhaust passage *t*. As the piston head 2 is larger in diameter than the piston head 3 and since the outer end of the piston head 3 is always open to exhaust the unbalanced pressure on the inner end of piston head 2 50 moves said piston head 2, main valve 6, and piston head 3 to the right. This closes passage *c* to pressure steam and opens said passage to exhaust through the cavity *m*, and passages *e* and *t*; thus exhausting pressure 55 steam in the cylinder A above the piston C. This movement of the main valve 6 also opens passage *d* to pressure steam which passes to the under side of the piston C and starts the upward stroke of said piston. 60 This movement of main valve 6, in addition, blanks the valve end of passage *i*, opens the valve end of passage *k* to exhaust through passage *p*, cavity *m*, and passages *e* and *t*, and connects the valve ends of passages *j* 65 and *l* by cavity *n*.

As the piston C nears the end of its upward stroke tripping port *j* is opened to pressure steam below the piston and said steam passes through port *j*, cavity *n*, passage *l* and enters behind piston head 4, forcing said piston head, auxiliary valve 7, and piston head 5 to the left; the outer end of the piston head 5 being open to exhaust through passage *k*, passage *p*, cavity *m*, and passages *e* and *t*. 75

When the auxiliary valve 7 moves to the left passage *j* is closed to exhaust and is opened to pressure steam which enters the space between the heads 4 and 5 through passage *b*. This pressure steam passes 80 through passage *f* and acting on the outer end of head 2 forces said head, main valve 6 and head 3 to the left; the outer end of the head 3 being open to exhaust through passages *h* and *t*. This closes passage *d* to 85 pressure steam and opens said passage to exhaust through cavity *m*, and passages *e* and *t*, thus exhausting the pressure steam in cylinder A below the piston C. This movement of the main valve 6 also opens passage 90 *e* to pressure steam which passes to the upper side of the piston C and starts the downward stroke thereof. In addition this movement of the main valve 6 blanks the valve end of passage *j*, opens the valve end 95 of passage *l* to exhaust through passage *o*, cavity *m*, and passages *e* and *t*, and connects the valve ends of passages *i* and *k* by cavity *n*.

In order to prevent premature actuation 100 of the auxiliary valve 7 and resulting short stroke of the piston C I provide the wall of the cylinder A adjacent each end thereof with cavities *r* and *s* which extend respectively on either side of the tripping ports *i* 105 and *j*. By reference to Fig. 4 it will be observed that should any pressure steam collect between the packing rings 8 and 9 it will be relieved to the exhaust end of the cylinder through the cavity *r* before the 110 space between said rings passes into communication with the tripping port *i*. If such structure were not provided and pressure steam between the packing rings should pass through the port *i* it would result in 115 premature movement of the auxiliary valve 7 and short stroke of the piston C.

What is claimed is:

1. In a fluid actuated valve mechanism, the combination of a piston and cylinder, 120 said cylinder having supply, exhaust and tripping ports, a main steam actuated valve for controlling said ports, an auxiliary valve for controlling the actuation of the main valve and moved by live steam pressure received from the cylinder through respective tripping ports at the end of each stroke of the piston, and means for relieving any pressure fluid collected between the cylinder and side face of the piston prior to the 125 130

movement of the zone of such collection into communication with the next active tripping port.

2. In a fluid actuated valve mechanism, 5 the combination of a piston and cylinder, said cylinder having supply, exhaust and tripping ports, a main steam actuated valve for controlling said ports, an auxiliary valve for controlling the actuation of the main 10 valve and moved by live steam pressure received from the cylinder through respective tripping ports at the end of each stroke of the piston, and means for affording communication between the exhaust end of the cylinder 15 and the zone of any collected pressure fluid between the cylinder and side face of the piston prior to the movement of such zone into communication with the next active tripping port.

20 3. In a fluid actuated valve mechanism, the combination of a piston and cylinder, said cylinder having supply, exhaust and tripping ports, a main steam actuated valve for controlling said ports, and an auxiliary valve 25 for controlling the actuation of the main valve and moved by live steam pressure received from the cylinder through respective tripping ports at the end of each stroke of the piston, said cylinder further having recesses in its inner wall extending on either 30 side of the tripping ports respectively for establishing communication between the exhaust end of the cylinder and the zone of any collected pressure fluid between the cylinder 35 and side face of the piston prior to the movement of such zone into communication with the next active tripping port.

4. In a fluid actuated valve mechanism, 40 the combination of a piston having packing rings and a cylinder, said cylinder having supply, exhaust and tripping ports, a main steam actuated valve for controlling said ports, an auxiliary valve for controlling the actuation of the main valve and moved by 45 live steam pressure received from the cyl-

inder through respective tripping ports at the end of each stroke of the piston, and means for relieving any pressure fluid collected between the packing rings prior to the movement of the space between said rings 50 into communication with the next active tripping port.

5. In a fluid actuated valve mechanism, 55 the combination of a piston having packing rings and a cylinder, said cylinder having supply, exhaust and tripping ports, a main steam actuated valve for controlling said ports, an auxiliary valve for controlling the actuation of the main valve and moved by live steam pressure received from the cylinder through 60 respective tripping ports at the end of each stroke of the piston, and means for establishing communication between the exhaust end of the cylinder and the space between the packing rings prior to the movement of 65 such space into communication with the next active tripping port.

6. In a fluid actuated valve mechanism, 70 the combination of a piston having packing rings and a cylinder, said cylinder having supply, exhaust and tripping ports, a main steam actuated valve for controlling said ports, and an auxiliary valve for controlling the actuation of the main valve and moved by live steam pressure received from the cylinder 75 through respective tripping ports at the end of each stroke of the piston, said cylinder having recesses in its inner wall extending on either side of the tripping ports respectively to establish communication between 80 the exhaust end of the cylinder and the space between the packing rings prior to the movement of such space into communication with the next active tripping port.

In testimony whereof I affix my signature, 85 in the presence of two subscribing witnesses.
